UNITED STATES PATENT OFFICE.

JOHN S. BRENNAN, OF MILWAUKEE, WISCONSIN.

WICK.

1,327,858.

Specification of Letters Patent. Patented Jan. 13, 1920.

Application filed August 18, 1919. Serial No. 318,121.

To all whom it may concern:

Be it known that I, JOHN S. BRENNAN, a citizen of the United States, and resident of Milwaukee, in the county of Milwaukee and State of Wisconsin, have invented certain new and useful Improvements in Wicks; and I do hereby declare that the following is a full, clear, and exact description thereof.

10 My invention pertains to new and useful improvements in annular wicks for use in the burners of heating and cooking stoves which burn gaseous or liquid hydro-carbons as a fuel.

15 It is well recognized that cotton and other wicks formed of combustible material are relatively inefficient in burners of the character mentioned, and this is equally true of wicks made from felted asbestos. In one 20 case the life of the wick is short because it quickly becomes charred, and in the other case it becomes clogged with soot or the like and prevents a ready capillary action of the liquid fuel when such is used. The disadvantages of both of these types of wicks may 25 be overcome by the use of a woven wick formed of threads or cords of asbestos. It is therefore the primary object of the invention to construct an annular wick of such 30 material.

It is also an object of the invention to provide a wick, the usefulness of which will be more than twice as great as that of the average wick of this character, this being carried 35 out by the provision of a burning edge on each peripheral edge of the annular wick.

A still further object is to provide a combined supporting strip for the wick material together with means for preventing the 40 unraveling of the non-selvaged edges of the same.

With these and other objects and advantages in view the invention resides in the novel features of construction and combination of parts which will be hereinafter particularly described and claimed.

Referring to the drawing forming part of this application,

Figure 1 represents a plan view of an annular wick constructed in accordance with 50 my invention.

Fig. 2 is a plan view of the metallic supporting strip used in connection with the strip of wick material.

55 Fig. 3 is a similar view of the wick before the same has been bent in circular shape.

Fig. 4 is an enlarged fragmentary view of a portion of the strip of wick material showing the manner in which the same is woven to form a strip of predetermined width and 60 having its opposite longitudinal edges selvaged.

Fig. 5 is a transverse sectional view taken substantially on the plane of the line 5—5 of Fig. 1.

65 In the illustrated embodiment of the invention as depicted in the drawing the numeral 1 denotes a strip of wick material of predetermined length, said strip being a portion of a strip of indeterminate length. In 70 other words the wick material can be woven in strips of any length and then cut into sections of the required length. As shown in Fig. 4 the wick material consists of warp 75 and woof threads or cords of asbestos woven together in an ordinary manner so that the opposite or longitudinal edges are selvaged.

The wick in addition to the strip of wick material includes a metallic supporting strip 2 of a length greater than the length of the 80 strip 1. The supporting strips 2 are preferably formed by stamping the same from blanks of very light gage sheet metal. Each 85 consists of a pair of parallel bars 3 and a plurality of transverse bars 4 together with end plates 5 which extend transversely of the bars 3 and are substantially of a length equal to the width of the strip 1. The intermediate portion of the metallic strip 2 between the end plate portions 5 thereof, or in 90 other words the distance between the bars 3, is less than the width of the strip 1. The ends of the transverse bars 4 beyond the outer edges of the bars 3 terminate in 95 prongs 6.

In making up a wick from one of the strips 1 of wick material and one of the metallic strips 2, the latter is placed on the former and extended longitudinally thereof with the longitudinal edges of the bars 3 100 equally spaced from the longitudinal selvaged edges of the strip 1. When the prongs 6 are bent laterally and forced into the wick strip 1 and then clenched as shown in Fig. 5, the two strips are effectively held together. 105 The end plates are thereafter bent longitudinally of themselves or transversely of the strip 1 so as to embrace the transverse unselvaged edges thereof. This will prevent such edges from becoming unraveled as is 110 obvious. The operation of shaping the straight strips 1 and 2 into circular form as

shown in Fig. 1 completes the operation of forming a wick of the character described.

In view of the fact that the immediate portions of the strip 2 are spaced inwardly 5 of the longitudinal peripheral edges of the strip 1, and since these last mentioned edges are selvaged, the wick can be disposed to present either of said selvaged edges as a burning edge. Thus one edge may be used until 10 it becomes frayed or otherwise mutilated or clogged, whereupon by reversing the wick a new and clean burning edge is had. Furthermore if so desired one of the metallic strips 2 may be used an indefinite number 15 of times merely by placing a strip of wick material such as the original strip when the latter becomes worn or otherwise rendered ineffective. Various changes may be made in the form and proportion and in the manner of assembling the several parts of the 20 invention without departing from or sacrificing any of the features thereof.

I claim:

1. An improved wick comprising a woven asbestos strip having its longitudinal edges selvaged, said strip being shaped to form a ring with its non-selvaged edges adjacent and parallel, and means for preventing said non-selvaged edges from unraveling.
2. An improved wick comprising a woven asbestos strip having its longitudinal edges selvaged, said strip being shaped to form a ring with its non-selvaged edges adjacent and parallel, and a supporting metallic ring 35 having the asbestos ring secured thereto, a portion of the metallic ring being bent around the non-selvaged edges of the asbestos strip to prevent the same from unraveling.
3. An improved wick comprising a rectangular strip of wick material and a me-

tallic strip secured to the strip of wick material and having its intermediate portion of less width than the width of the latter, the opposite end portions of the metallic strip 45 being substantially the same width as the first mentioned strip and bent around the transverse edges of said first mentioned strip, said strips being shaped to form a ring with the last mentioned edges adjacent and parallel. 50

4. An improved wick comprising a rectangular strip of woven material having its longitudinal edges selvaged, a metallic strip secured to the woven strip and having its intermediate portion of less width than the width of the woven strip, the opposite end portions of the metallic strip being substantially the same width as the woven strip and bent around the non-selvaged edges of the 60 latter to prevent the same from unraveling, said strip being shaped to form a ring.

5. An improved wick comprising a rectangular strip of woven material, a metallic strip of rectangular shape disposed in contact with the other strip and having its intermediate portion of less width than the width of the first mentioned strip, the opposite end portions of the metallic strip being of substantially the same width as the 65 width of the first mentioned strip and bent around the transverse edges of the latter, and prongs extending from the longitudinal edges of the intermediate portion of the metallic strip and bent into the other strip to 70 secure the two strips together, said strips being shaped to form a ring.

In testimony that I claim the foregoing I have hereunto set my hand at Milwaukee, in the county of Milwaukee and State of Wisconsin.

JOHN S. BRENNAN.
